US00D804906S

(12) **United States Design Patent** (10) **Patent No.:** **US D804,906 S**
Diener et al. (45) **Date of Patent:** **** Dec. 12, 2017**

(54) **INSULATED BOTTLE**

(71) Applicants: **Ryan Diener**, Bend, OR (US); **Brian Goodwin**, Bend, OR (US); **Benjamin Hein**, Bend, OR (US)

(72) Inventors: **Ryan Diener**, Bend, OR (US); **Brian Goodwin**, Bend, OR (US); **Benjamin Hein**, Bend, OR (US)

(73) Assignee: **HELEN OF TROY LIMITED**, St. Michael (BB)

(**) Term: **15 Years**

(21) Appl. No.: **29/563,781**

(22) Filed: **May 7, 2016**

(51) LOC (10) Cl. **07-01**

(52) U.S. Cl.

USPC **D7/510**; D7/511; D7/523; D7/532

CLAIM

The ornamental design for an insulated bottle, as shown and described.

DESCRIPTION

FIG. 1 is a perspective view of an insulated bottle showing our new design;

FIG. 2 is a side view of the insulated bottle;

FIG. 3 is a top view of the insulated bottle; and,

FIG. 4 is a bottom view of the insulated bottle.

1 Claim, 4 Drawing Sheets
